UNITED STATES PATENT OFFICE.

ARCHIE P. FAHNESTOCK, OF PLANDOME, NEW YORK.

ELECTRIC SWITCH.

Application filed November 22, 1921. Serial No. 517,097.

To all whom it may concern:

Be it known that I, ARCHIE P. FAHNESTOCK, a citizen of the United States, residing at Plandome, Long Island, in the county 5 of Nassau and State of New York, have invented certain new and useful Improvements in Electric Switches, of which the following is a specification.

This invention relates to electric switches 10 and more particularly to switches of the push button type for making and breaking the circuit of conductors.

It is a desideratum in electric switch construction, and especially where the switch is 15 to be used in a location where it is subjected to vibration and jarring, that the conductors be securely gripped in a manner that will not be affected by such vibration or jarring. It has heretofore been proposed to employ a 20 spring binding post of the type disclosed in Reissue Letters Patent of the United States No. 12,642 issued April 28, 1907, to John Schade, jr., for securing the conductors and the use of such posts have proved satisfactory 25 in overcoming the difficulties just adverted to.

The object of the present invention is to provide the advantage of a perfect and permanent electrical contact in a small push 30 button switch of the common circular type. To this end one feature of the invention relates to a proper securement of spring binding posts, of the kind referred to, on the base board of a circular push button switch. 35 Another feature relates to a simple arrangement of the electrical contacts insuring an effective and durable electrical connection when the button is depressed.

To the accomplishment of the above object, and such others as may appear from the following description, the invention comprises the features and combinations of parts hereinafter described and then particularly pointed out in the appended claims.

The preferred form of the invention is 45 shown in the accompanying drawings, in which:

Figure 1 is a view, in plan, of a round push button switch in which the invention is 50 embodied; Fig. 2 is an underside view of the switch; Fig. 3 is a view, in plan, of the base board and attached parts, removed; Fig. 4 is a view, in plan, of the base board alone; Fig. 5 is a central sectional view of the assembled parts; Fig. 6 is a view, in side elevation, of one of the spring terminal clips;

and Fig. 7 is a fragmental section of the base board. In Figs. 1, 2, and 3 the switch is shown with wires attached, but the wires are not shown in Fig. 5 to permit a clearer view 60 of the parts.

In the embodiment of the invention illustrated in the accompanying drawings the switch comprises a housing 10 having a central opening for a button 11, and closed at its 65 open side by a base board 12. The base board is stamped from suitable insulating material and is punched with holes 13 for securing screws, holes 14 for the terminals and oppositely disposed marginal slots 15 70 for the wires. It is also provided on one surface with two pairs of protuberances 16 and 18 struck up from the material of the base board in the manner fully shown by Fig. 7, the purpose of which will appear 75 later. The housing is provided with screw holes 19, as usual.

A pair of spring binding posts 20 and 21 are riveted at 22 and 23 to the base board through the holes 14. These posts are of the 80 well-known "Fahnestock" type, fully disclosed in said patent to Schade and, therefore, need not be described in detail except to point out that the reversely bent end of the usual hook-shaped resistant member 24 85 (Fig. 6) is shortened to such an extent that a terminal wire, bent as shown in Fig. 3, may be placed thereunder from above said hook by a downward movement relative to the post when the spring member of the post 90 is depressed to project the hook through the receiving slot in said member. (See dotted lines Fig. 6.) The binding posts 20 and 21 are placed in parallel location, with their 95 resistant members substantially opposite the wire-receiving slots 15 to facilitate connecting the wires, and their body members lying between and in contact with the pairs of protuberances 16 and 18, respectively. The purpose of the protuberances is to prevent 100 turning of the posts on their rivets, under adverse conditions of use such as hereinbefore adverted to, thus insuring their required position on the base board without the necessity of an additional rivet or other separate 105 means of securement.

A contact piece 25, stamped from sheet metal, extending to the center of the base board, is secured to the post 20 by its rivet 22. A similar contact piece 26, bent to overlie the portion of the piece 25 between the 110 posts is secured to the post 21 by its rivet

23. The contact piece 26 forms a leaf spring which underlies the button 11 and maintains it pressed outwardly through its hole in the housing 10. It is within the scope of the invention to make the binding post and contact piece in one piece, if so desired.

The switch operates like any other push button switch, a depression of the button causing the contact 26 to engage the contact 25 and thus close the electrical circuit through the wires attached, as shown in Fig. 3, to the binding posts 20 and 21 but the advantages over a push button switch employing screw binding posts will be obvious to those skilled in the art. The simplicity of construction, the ease in securing the terminals in place eliminating any winding of the wires, the absence of loose wire-securing parts that may be lost, and the insurance of electrical contact under extremely adverse conditions, all combine in producing practical perfection in push button switches.

The nature and scope of the invention having been indicated and its preferred form having been specifically described, what is claimed as new, is:—

1. An electric switch comprising a base board having marginal wire-receiving slots, a pair of spring binding posts riveted to said base board with their wire-gripping portions substantially opposite said slots, means to prevent the turning of said posts on their rivets, two normally separated contact pieces one extending from each post, and means for forcing said pieces into engagement to close the circuit.

2. An electric switch comprising a base board having marginal wire-receiving slots, a pair of spring binding posts secured to

said base board with their body members in parallel relation and their resistant members substantially opposite said slots, means on the base board to maintain said parallel relation, said body members being provided with extensions curved inward to form contact pieces arranged in overlying relation between said binding posts, and means for completing and interrupting the circuit by movement of one of said contact pieces.

3. An electric switch comprising a base board, two spring binding posts and two overlying contact pieces, secured to said base board by two rivets each passing through a post, a contact piece and the base board, and means for causing relative movement of said contact pieces to complete and interrupt the circuit.

4. An electric switch comprising a base board, a pair of spring binding posts secured thereto with their body portions in parallel relation, and protuberances struck up from the material of the base board at opposite side of said body portions for maintaining said parallel relation.

5. An electric switch comprising a base board having marginal wire-receiving slots, two "Fahnestock" spring binding posts secured thereto each having its resistant member substantially opposite a slot and formed with short hooked ends to permit a terminal wire in the adjacent slot to be placed thereunder from above said hook, means for maintaining said posts in fixed position on the base board, contact pieces electrically connected to said binding posts, and means for causing engagement between said contact pieces to close the circuit.

ARCHIE P. FAHNESTOCK.
